Des. 67,843

UNITED STATES PATENT OFFICE.

IRVING MILLER, OF NEW YORK, N. Y.

DESIGN FOR A BOX.

Application filed May 23, 1925. Serial No. 13,543. Term of patent 3½ years.

To all whom it may concern:

Be it known that I, IRVING MILLER, a citizen of the United States, residing at 255 West 88th Street, New York city, New York, have invented a new, original, and ornamental Design for Boxes, of which the following is a specification, reference being had to the accompanying drawing, forming part thereof.

In the drawing:

The figure is a perspective view of a box.

I claim:

The ornamental design for box, as shown.

IRVING MILLER.
